ELLEN W. DECKER, OF SOUTH ORANGE, NEW JERSEY

STOCKING

Application filed October 20, 1931. Serial No. 569,946.

My invention relates to improvements in stockings and more particularly to the means for the attachment of the garter to the welt or upper part of lady's silk stockings of sheer or fine knitted fabric.

The provision of means such as looped tapes or buttonholes on the garter welts of sheer fabric stockings for attachment of the garter is well known in the art, and one object of my invention is to provide an improved form of loop and the combination thereof with button holes. A further object is to provide a method of manufacture or of attaching the loops to the garter welt to improve the appearance and effectiveness of the attachment while simplifying and improving the method of production.

With these and other objects in view the invention consists in the improved method of attachment of the loops and in the improved form of loops and buttonholes as shown by way of illustration or example on the accompanying drawing on which:

Fig. 1 is a perspective view of the upper part of a stocking showing the garter welt and embodying my improved garter-attaching means;

Fig. 2 is a perspective view of a garter welt showing a slightly modified form of the garter-attaching means;

Fig. 3 is a similar view showing another form of garter-attaching means with a leg encircling garter applied thereto;

Figs. 4 and 5 are detail views of the garter-attaching means on the inner surface of the welt and shown at two different stages in the manufacture of the final product;

Fig. 6 is a detail view similar to Fig. 5 but showing a modified form of the attaching means.

On the drawing the welts 1 are of usual form and are provided in the usual way at the upper extremities of the stockings 2 which have the usual back seams 3 in the case of stockings of the "full-fashioned" type.

Referring to Figs. 1 to 3 inclusive, tape loops 4 are attached to the inner surface of the welt 1 at the upper extremity thereof so that the loops, which are given a half twist upon themselves as shown, project above the edge 5 of the stocking and may be conveniently engaged by the usual garter clip 6 as shown at Fig. 1. In order to provide alternative receiving means for the garter-clips 6 the loops 4 and the stocking welts 1 have button holes 7 cut therein and these holes 7 are provided with button-hole-stitching 8 which may serve the double purpose of outlining the raw edges of the holes and of providing a very strong and permanent connection between the loops 4 and the welt to take the pull of the garter.

Referring to Figs. 4 and 5, after the stocking has been knit and while still a flat piece of fabric, the tape loops are placed on the inner surface of the welt at the upper edge thereof as shown in Fig. 4 and are preferably secured to the knitted fabric by parallel lines of stitching 9, 10 to hold them permanently in place. The button hole 7 is then cut through both thicknesses of tape and stocking welt and the button-hole-stitching 8 is then applied. The back seam of the stocking is then formed and the stocking is degummed, dyed and finally dried so as to produce the finished stocking which is shrunk to a substantial extent from the dimensions of the flat fabric to which the loops were attached. The tape material of which the loops 4 are made, however, does not shrink, and as a consequence, the tape may be slightly puckered and the button-hole opens up with the shrinking of the stocking fabric as is clearly shown in Fig. 5.

From the foregoing it will be understood that the loops 4 are made of a material that does not shrink when the stocking is subjected to the usual degumming, dyeing and drying process, and it will be readily appreciated that the usual shrinkage of the

knitted fabric during this process results in an attachment of the parts concerned having the characteristic feature that the knitted fabric must be stretched to some extent before tension is transmitted to the loop. Fig. 4 shows the parts before shrinking of the knitted fabric and Fig. 5 shows the parts after the shrinking has taken place.

It will be readily apparent that by reason of the secure attachment of the tapes 2 to the welt 1, by the lines of stitching 9, 10 and by button-hole stitching the pull of the garter will be evenly distributed along both sides of the button-hole and because of the puckered or unstretched condition of the tapes 4 due to shrinkage of the stocking fabric, the pull of the garter upon the tapes is first taken up by the tape itself until the tape is under tension and the button hole is drawn together and the pull is evenly distributed to the welt itself. The tapes 4 having been dyed with the stocking, the color and appearance of the finished stocking is of course perfectly harmonious.

In the form illustrated at Fig. 2 each tape loop 4 has two button holes 7 so as to provide three selective means of attachment for the garter to suit legs of different lengths, while the form shown at Fig. 6 has twin loops 4 and pairs of button holes 7 to provide four means of attachment for the same purpose.

The arrangement illustrated at Fig. 3 has four loops arranged at suitable points around the circumference of the welt and the four button holes 7 are adapted to receive a leg-encircling band 11 which is preferably of elastic material and has buckles or clasps 12 for the attachment thereof around the leg for use with, or in lieu of the usual garters 6.

Although the drawing and above specification disclose the best mode in which I have contemplated embodying my invention, and the best method of producing the finished article I desire to be in no way limited to the details of such disclosure for in the further practical application of my invention, many changes may be made in the details of the construction and method, as circumstances require or experience suggests, without departing from the spirit of the invention within the scope of the appended claims.

What I claim is:—

1. A stocking of shrinkable material having garter attaching means comprising a plurality of garter-receiving members of substantially unshrinkable material and stitching attaching said members to the stocking with said members in a slightly puckered or unstretched condition so as to be under tension only when the stocking is stretched due to the pull of the garter, so as to properly distribute the garter pull.

2. A stocking of shrinkable material having garter attaching means comprising a plu-

rality of garter-receiving members of substantially unshrinkable material and stitching attaching said members to the stocking with said members in a slightly puckered or unstretched condition so as to be under tension only when the stocking is stretched due to the pull of the garter, so as to properly distribute the garter pull, and having button-holes formed in said garter-receiving members.

In testimony whereof I have signed my name to this specification.

ELLEN W. DECKER.
